BATH MAT

Ellie J. Huggins, Wheaton, Ill., assignor to Pretty Products, Inc., Coshocton, Ohio

Filed Feb. 14, 1972, Ser. No. 226,398

Term of patent 14 years

Int. Cl. D6—II

U.S. Cl. D6—211

FIG. 1 is a top plan view of a bath mat embodying my design.

FIG. 2 is a front side elevational view of the bath mat of FIG. 1.

FIG. 3 is a fragmentary vertical sectional view on an enlarged scale taken along line 3—3 of FIG. 1.

FIG. 4 is a fragmentary vertical sectional view on an enlarged scale taken along line 4—4 of FIG. 1.

I claim:

The ornamental design for a bath mat, as shown.
